COIN INSERTION SAVING DEVICE IN
CLOCKS, COUNTERS, AND LIKE MOTION
WORKS

Charles Rosat, deceased, late of Boudry, Switzerland, by Rose-Lucy Rosat, née Bôle, administratrix, Boudry, Switzerland, and Anders Torsten Hammarstrand, Djursholm, Sweden

Application December 4, 1930, Serial No. 500,096,
and in Switzerland January 31, 1930

7 Claims. (Cl. 194—19)

It is known to associate a saving device with clocks having a coin insertion slot for the purpose of awakening the sense of saving in the owner of the clock, the clock being arranged to be stopped although its operating spring is tensioned, when the owner discontinues inserting coins resulting in saving. Most clocks provided with such a saving device have a control lever located in a coin insertion groove and serving to act upon the clock movement so as to stop the clock when the insertion of coins is discontinued. The attention of the owner is drawn to his duty of inserting a coin by the stopping of the clock, even if the latter is still wound up.

15 The present invention relates to a saving device in clocks, counters and like motion works, in which in a like manner, the continued operation of the driving mechanism of the motion work is ensured by the insertion of coins by means of a controlling member located in a coin insertion groove and serving to control the said mechanism.

According to the present invention the saving device comprises a step by step advancing mechanism controlled by the action of said controlling member in dependence of the insertion of coins and adapted to cause, when not being so controlled, in a predetermined position the locking of the motion work driving mechanism (clock movement and the like), said advancing mechanism being so interconnected with the motion work driving mechanism that it advances at each coin insertion away from its locking control position, whilst when the insertion of coins is discontinued for a sufficiently long time, it is caused to turn back by the action of the driving mechanism towards its locking control position so far as to finally arrest same.

40 Preferably, the controlling member is constituted by an escapement lever cooperating with an escapement wheel adapted to effect the arrest of the driving mechanism, the escapement wheel being arranged to rotate step by step through one tooth at a time each time a coin is inserted, such rotation being permitted by oscillation of the escapement lever, but to be rotated backwards again periodically by means of a tensioned member or another part of the driving mechanism in order that when the insertion of coins for the purpose of saving is continued, it may not come into the position in which it effects the arrest of the driving mechanism. The escapement wheel and the escapement lever associated therewith play an important part, inasmuch as these parts constitute a simple means for release by means of coins, and also for controlling the

arrest of the driving mechanism and for ensuring an indication or counting of the strokes of the escapement wheel still available till up to the arrest of the mechanism.

The accompanying drawing illustrates an embodiment of the invention as applied to a clock, which as a whole may be called a "saving clock" for short; for the sake of clearness, only the parts necessary for understanding the invention, are illustrated. Figure 1 is a rear view of the saving clock; Figure 2 is a section on the line II—II of Figure 1; Figure 3 is a vertical section similar to Figure 1, turned 180°, and Figure 4 is a plan view of a detail of Figure 3.

15 Figure 1 is a coin insertion groove member provided with a controlling or escapement lever 3, pivotally mounted at 2, one end of which extends into the coin insertion groove under spring action so as to block said groove. The lever 3 is provided with escapement pins 4, 4^a, which alternately engage the teeth of an escapement wheel 6 rotatably mounted at 5 on the wall of the coin insertion slot member 1. On a pin 7 of the wheel 6 the inner end of a spiral spring 9 is supported, the other end of the spring 9 being connected to 20 a casing or barrel 8 on the wall of the slot member 1. The escapement wheel is also provided with an arresting pin 10 extending through the wheel, the part of the pin 10 projecting forwardly being adapted to cooperate with an angle lever 12 adapted to influence the balance wheel 11 of the clock movement.

25 The lever 12 is pivotally mounted at 12^a and is held by a spring 13 in its normal position in which its leaf spring 12^b is disengaged from the balance wheel 11. The spring 13 acts on the other hand upon the escapement lever 3.

30 The coin insertion groove member 1 is moreover provided (Figures 3 and 4) with a toggle member 14 pivotally mounted at 14^a and having a pin 14^b to which a tension spring 15 is connected. A finger 16 seated on the axle 17 of a star wheel 18 is adapted to cooperate with the pin 14^b.

35 The star wheel 18 is operated by the clock movement in such a manner that it effects in a predetermined interval of time, a complete rotation. Whilst the arresting pin 10 cooperates by its forward portion with the lever 12, it also projects rearwardly to cooperate with a stroke limiting pin 19, the rear end 10^a of the pin 10 on the escapement wheel 6 being arranged to come into contact with the pin 19 during rotation of the wheel so as to stop the operation of the mechanism.

The escapement wheel 6 may at the same time serve as counting wheel, as will be explained hereinafter.

The operation of the "saving clock" is as follows:

When a coin is inserted in the groove 1, it rocks the escapement lever 3, with the result that the escapement pin 4 is moved out of the path of the teeth of the wheel 6 and the escapement pin 4^a is moved into the same, so that the wheel 6 rotates, under the action of the tensioned spiral spring 9, for about half of a tooth in the direction of the arrow *v*. Directly after, the coin releases the escapement lever 3 so that it assumes its previous position under the action of spring 13 and the escapement wheel is stopped upon a further rotation of one half of a tooth. These operations take place every time a coin is inserted. The arresting pin 10 will therefore move step by step, more and more approaching the stroke limiting pin 19.

But in the meantime the finger 16 has rotated with the star wheel 18 to such an extent as to engage the pin 14^b of the member 14 and turn the latter around the pivot 14^c so that when the spring 15 reaches its dead point position with the finger 16 at the other side of the axle 17, the member 14 is moved rapidly into the path of the teeth of the escapement wheel 6 with a jerk, by means of the tension spring 15, so as to rotate the wheel in the reverse direction to that of the arrow *v* thus retensioning the spiral spring 9.

The movements of the various parts are, of course, so proportioned that this takes place long before the pin 10 of the wheel 6 is approaching the stroke limiting pin 19.

Should saving be discontinued, i. e. should coins not be inserted in the groove 1 for a time, the advancing rotation i. e. rotation in the direction of the arrow *v* of the escapement wheel 6 does not take place, but, on the other hand, its rotation in the reverse direction under the action of the member 14 operated by the clock movement is continued, so that the pin 10 of the wheel 6 comes into contact with the locking lever 12 so that the latter brakes the balance wheel 11 by means of the leaf spring 12^b, and stops the clock movement, even when its operating spring is wound up. Thus the saver is reminded of his duty to insert further coins.

The escapement wheel 6 serves at the same time as a counting wheel. Each tooth of the wheel 6 corresponds to the insertion of a coin; accordingly, a number plate or graduation is provided directly on the wheel 6, although this number plate could be provided on a disc which is separate from, but connected to the escapement wheel. The number of coins inserted can therefore be ascertained, the figures of the wheel being arranged to be observed through a suitable opening, or the number of reverse rotary steps of the wheel to be effected before the clock movement is stopped.

The coin insertion groove member 1 is provided adjacent the place where the coin acts on the lever 3 with an interchangeable filling member 1^a, so that by interchange of the latter for a wider or narrower member, the width of the slot for certain different sizes of coins can be readily adjusted.

What we claim is:—

1. A coin insertion saving device in clocks, counters, and like devices employing motion works, comprising means defining a coin insertion groove, driving mechanism for the motion works,

a lever for locking the said driving mechanism, an escapement wheel, means constantly tending to rotate said escapement wheel, an escapement lever extending into said coin insertion groove, and associated with said escapement wheel, means on said escapement wheel for controlling said locking lever, the said escapement lever, under energy imparted thereto by the passage of coins through the groove, controlling the escapement wheel for a step by step motion thereof in a direction away from the operable position of said means for controlling the locking lever, means constantly actuated by said driving mechanism for periodically moving said escapement wheel in a reverse direction, towards the operable position of said means for controlling the locking lever, in such manner that when the insertion of coins is discontinued, the means on the escapement wheel will actuate the locking lever to stop the driving mechanism.

2. A coin insertion saving device in clocks, counters, and similar devices employing motion works, comprising means defining a coin insertion groove, a driving mechanism for the motion works, a lever for locking said driving mechanism, an escapement wheel, an escapement wheel lever partly extending into said coin insertion groove, and adapted to control said escapement wheel, said wheel being adapted to actuate said locking lever, a spiral spring normally tending to rotate said escapement wheel, whereby, under the control of the escapement lever the said wheel is advanced step by step in a direction away from its operable position for actuating the locking lever, means constantly actuated by said driving mechanism for periodically moving said escapement wheel in a reverse direction, towards its operable position for actuating the locking lever, in such manner that when the insertion of coins is discontinued, the escapement wheel will actuate the locking lever to stop the driving mechanism.

3. A coin insertion saving device in clocks, counters, and similar devices employing motion works, comprising means defining a coin insertion groove, a driving mechanism for the motion works, a lever for locking said driving mechanism, an escapement wheel for actuating said locking lever, an escapement lever partly extending into said coin insertion groove, and adapted to control said escapement wheel, a spiral spring adapted to rotate said escapement wheel, thereby imparting thereto, under the control of the escapement lever, a step by step advance in a direction away from its operable position for actuating said locking lever, means constantly actuated by said driving mechanism to periodically rotate said escapement wheel in a reverse direction, towards its operable position for actuating lever, so that upon discontinuance of the insertion of coins, the escapement wheel will actuate said locking lever to interrupt the driving mechanism, said last-mentioned means causing the rewinding of the said spiral spring.

4. A coin insertion saving device in clocks, counters, and similar devices employing motion works, comprising means defining a coin insertion groove, a driving mechanism for said motion works, a locking lever for said driving mechanism, an escapement wheel for controlling said locking lever, an escapement lever partly extending into said coin insertion groove, for controlling said escapement wheel under the impulses from coins inserted therein, means constantly tending to rotate said escapement wheel,

said escapement wheel being advanced step by step, under the control of said escapement lever, in a direction away from its operable position for actuating the locking lever, means constantly actuated by said driving mechanism for periodically moving said escapement wheel in its reverse direction towards its operable position for actuating said locking lever so that upon discontinuance of the insertion of coins in the groove, the escapement wheel will actuate said locking means to interrupt the driving mechanism, the means for periodically reversing said escapement wheel comprising a spring biased toggle member movable with a rapid, jerky motion into cooperation with the escapement wheel, and so connected with the driving mechanism as to be tensioned periodically.

5. A coin insertion saving device in clocks, counters, and similar devices employing motion works, comprising means defining a coin insertion groove, a driving mechanism for the motion works, a lever for locking said driving mechanism, an escapement wheel for actuating said locking means, means constantly tending to rotate said escapement wheel, an escapement lever partly extending into said coin insertion groove, the said escapement lever, actuated by the passage of coins through said groove, controlling said escapement wheel in such manner that the latter is adapted to advance step by step, in a direction away from its operable position for actuating the locking means, means constantly actuated by said driving mechanism for periodically moving said escapement wheel in the reverse direction, so that upon failure to insert coins in the groove, the escapement wheel will actuate said locking lever to discontinue said driving mechanism, and counting means connected with said escapement wheel, to indicate the number of steps made by the escapement wheel.

6. A coin insertion saving device in clocks, counters, and similar devices employing motion works, comprising means defining a coin insertion groove, a driving mechanism for the motion works, means for locking said driving mechanism, an escapement wheel for actuating said locking means, means constantly tending to ro-

tate said escapement wheel, an escapement lever extending partly in said coin insertion groove, and adapted, under the influence of the passage of coins through the groove, to control the movement of the escapement wheel, the said escapement wheel being adapted, under the control of said lever, to advance step by step, as an incident to the passage of coins, in a direction away from its operable position for actuating the locking means, means actuated by said driving mechanism to rotate said escapement wheel periodically in the reverse direction, so that upon failure to insert coins in the groove, the escapement wheel actuates the locking means to discontinue the driving mechanism, and an elongated interchangeable filling bar placed directly in said insertion groove to adapt it for coins of different sizes.

7. A coin insertion saving device in clocks, counters and the like, comprising means defining a coin insertion groove, a driving clock-work mechanism, a stopping lever for said clock-work mechanism, an escapement wheel for controlling said stopping lever, a spiral spring actuating said escapement wheel, an escapement lever partly 100 extending into said coin insertion groove, for controlling said escapement wheel under the impulses from coins inserted therein, said escapement wheel being advanced step by step, under the control of said escapement lever, in a direction 105 away from said stopping lever, means actuated by said clock-work mechanism for periodically moving said escapement wheel in its reverse direction towards said stopping lever so that upon discontinuance of the insertion of 110 coins in the groove, the escapement wheel will actuate said stopping lever to stop the clock-work mechanism, the means for reversing said escapement wheel comprising a spring-biased toggle member movable with a rapid, jerky motion into 115 cooperation with said escapement wheel, and so connected with the clock-work mechanism as to be tensioned periodically.
